UNITED STATES PATENT OFFICE.

CHARLES V. STRICKLAND, OF WINSTON-SALEM, NORTH CAROLINA, ASSIGNOR TO R. J. REYNOLDS TOBACCO COMPANY, OF WINSTON-SALEM, NORTH CAROLINA, A CORPORATION OF NEW JERSEY.

PINTLE-INSERTING MACHINE.

Original application filed July 29, 1919, Serial No. 314,013. Divided and this application filed June 22, 1921. Serial No. 479,585.

To all whom it may concern:

Be it known that I, CHARLES V. STRICKLAND, a citizen of the United States, and resident of Winston-Salem, in the county of 5 Forsyth and State of North Carolina, have invented certain new and useful Improvements in Pintle-Inserting Machines, of which the following is a specification.

My invention relates to a hinge forming 10 machine, and especially to a machine for attaching hinge pintles to sheet metal blanks. It is particularly applicable to machines of the type shown in the United States patent to Richter, No. 1,096,863 issued May 19, 15 1914, the invention set forth in this specification being a division of that disclosed in my copending application Ser. No. 314,013, filed July 29, 1919, now Patent No. 1,413,627 dated April 25, 1922.

20 Machines of this general nature handle a sheet metal blank, which may either be flat or formed into any other shape, the preferred type operating on flat blanks. The blanks are provided with suitable projecting 25 elements, which the machine wraps about a wire pintle automatically cut off and brought into engagement with the blank elements. By this operation the pintle is permanently mounted on the blank with 30 spaces between the blank elements where the pintle may be engaged by the similar elements of the other hinge member.

Machines of this type have heretofore 35 been operated as separate units, the pintled blanks being discharged by the machine into any suitable receptacle and delivered to the operator of the machine which forms the blanks into metal container bodies.

A principal object of my invention is to 40 provide a pintle inserting machine which will deliver its product directly to the body forming machine. A corollary object is to provide means for insuring the accurate registration of the delivered blanks in proper 45 position on the body forming machine to be engaged by the operating mechanism of the latter.

Another object is to so arrange and construct the parts of a pintle inserting machine of the type indicated that it can readily be actuated by the driving mechanism

of the body forming machine, and preferably so that the pintle forming machine is mounted on the body former substantially as an attachment thereto, with the obvious 55 resultant saving in floor space, construction expense and operating difficulty.

Other objects and advantages of my invention will be apparent from the following description, taken in connection with the accompanying drawings, in which:

The single figure is a front elevation of the entire machine mounted on a standard type of body forming machine, parts being broken away.

65 The form of pintle inserting machine disclosed in the preferred form illustrated is described in detail in my above mentioned Patent No. 1,413,627, and is of the general type shown in the Richter patent. As my 70 present invention relates to the combination of this machine with the body former, I will set forth merely the important features of the pintle inserting mechanism, reference being made to my abovementioned patent 75 and the Richter patent for a detailed description of the parts.

The flat metal blanks 25, preferably lithographed, are fed into the machine by hand, a stack of blanks being shown on the platform 42^a at the left of the machine. They are placed by the operator on a reciprocating feed plate or bar 33, provided with spaced feed dogs 43 which are spring pressed upwardly the outer end of each dog projecting 80 slightly above the upper surface of the feed bar and engaging the rear edge of a blank and advancing it during the forward stroke of the feed bar from left to right. On the return of the feed bar the blanks are held in stationary position by various friction devices, the dogs 43 sliding under the blanks. The feed bar is reciprocated by a rock arm 36 pivoted on the frame and connected to the feed bar by a link 35, arm 36 being oscillated by pitman 37.

85 While in stationary position, the edges of the blanks are first cut to shape by the cutter 61, and then provided with pintles attached thereto by a pintle inserting mechanism, the 100 main operative portion of which is indicated at 66, this portion being adapted to engage

tongues on successive blanks with wire pintles. The cutter 61 and pintle applying mechanism 66 are mounted on a vertical reciprocating ram 50 connected to a crank on shaft 54, so that a blank is cut away and the successive blank provided with a pintle at each descent of ram 50, while the blanks are held in stationary position during the return of feed bar 33.

10 The machine is also provided with a device, indicated generally at 100^a, which is arranged to feed forward intermittently a continuous wire to provide suitable pintle lengths, one of which is cut off and engaged 15 by the pintle forming element 66 at each descent of the ram 50. The wire feeding device 100^a is operated by a pitman 93.

The body forming machine includes a frame 23 carrying a drive shaft 42, and provided with a guideway or channel 124^a along which the pintled blanks are advanced by suitable mechanism into engagement with the devices which form therefrom container bodies.

25 I have so constructed and arranged the pintle inserting machine that it will deliver blanks to the feed channel 124^a of the body former in proper position for operation thereby. I have accomplished this result by 30 locating the pintle inserting machine in position so that the feed bar 33 extends substantially at right angles to the feed channel 124^a and into juxtaposition thereto, so that the last feeding movement to the right imparted to a blank by the feed bar will locate it with considerable accuracy across channel 124^a. With the type of body former now in 35 general use and illustrated in the drawing, the blank will be positioned properly for engagement by the operating mechanism of 40 the body former.

I may also provide suitable mechanism for insuring the accurate registration of the blanks on the body machine feed, so that the 45 carriage of the latter will engage them without any manipulation by the operator. This mechanism may consist of a lever 119 pivoted on a bracket 120 mounted on the bed of the body former, one end of the lever carrying a roll 121 engaging cam slot 122 in cam 123. The opposite end of lever 119 carries 50 positioning plate 124 mounted adjacent to the end of the pintle machine feed and shaped to guide and hold the pintled blank 55 in accurate position on the feedway of the body machine. It will be noted that the positioning plate 124 is so contoured and particularly recessed at its lower face, so as to clear the carriage of the body former 60 which travels along the feedway 124^a, conveying the successive pintled blanks into the body forming mechanism.

I also provide means whereby the operation of the pintling machine and that of the

means for registering the blanks on the body former are synchronously operated. In general I accomplish this object by providing direct connection between the driving mechanism of the pintling machine and that of the registering device. In the form 70 shown, I have also provided a simple driving construction for all of the parts indicated, which further assures complete synchronization between the pintling machine and the body former. I have accomplished this 75 object by driving all of such devices from a vertical shaft 40 suitably driven from the shaft 42 of the body former. Pitman 37, which operates the feed bar, is actuated by cam 39; pitman 93 operating the wire feed 80 is actuated by cam 97; and both of said cams, together with cam 123 which operates the blank registering device, are directly mounted on shaft 40. The latter shaft also drives, by suitable gear connection, shaft 54 85 which operates the blank cutting and pintle attaching devices. Obviously various other driving arrangements may be employed, the one illustrated being primarily advantageous because of its simplicity and convenient arrangement.

The operation of the machine is as follows. As heretofore indicated, successive blanks 25 are located on the left-hand end of feed bar 33, which shifts the successive 95 blanks step by step toward the right, the blanks being excised when under the cutter 61, and provided with pintles when under the pintling device 66. From the latter station they are advanced step by step until 100 the final impulse from feed bar 33 projects them into position across the feed channel 124^a of the body former. During the latter motion the registering plate 124 is maintained in elevated position by cam 124; but as soon as the blank is located on the body former channel the registering plate 124 is depressed, positioning the blank accurately on said channel and preferably maintaining it in such position until the body former carriage has engaged the blank and advanced it along the channel. The registering plate 124 is then elevated to receive the next blank, the feed of the pintle inserting machine being suitably synchronized 110 with that of the body former, as by driving connections of the type indicated.

It will be apparent that substantial modifications and changes may be made in the various elements, and particularly in the type of mechanism employed for inserting pintles in the blanks and for feeding them forward. My invention therefore is not limited to the particular arrangement shown, but may be substantially varied as indicated by 125 the scope of the following claims.

I claim:

1. In a machine of the class described, the

combination with a container body forming machine having a guideway, of a blank conveyor adapted to deliver pintled blanks to said guideway, and means for attaching pintles to blanks on said conveyor.

2. In a machine of the class described, the combination with a container body forming machine of pintle attaching mechanism, blank conveying mechanism adapted to deliver a blank successively to the pintle attaching mechanism and then to the body forming machine, and drive means connected to the pintle attaching means and the conveying means, and actuated by the driving mechanism of the body forming machine, the construction being such that said means, mechanism and machine operate in synchronism.

3. In a machine of the class described, the combination with a container body forming machine having a guideway for blanks, of means for attaching pintles to successive blanks, means for delivering the blanks successively to the attaching means and then to the guideway, a shaft connected to the drive of the body forming machine, and driving means between said shaft, the pintle attaching means and the blank delivering means, for operating both of said means in synchronism with said machine.

4. In a machine of the class described, the combination with a container body forming machine having a guideway for blanks, of pintle attaching mechanism including means for feeding a continuous wire to form successive pintle lengths, means for severing said lengths and attaching them to blanks, means for delivering blanks successively to the attaching means and then to the said guideway, a drive unit connected to the driving mechanism of the body forming machine, and separate driving connections between each of said means and said unit to provide synchronous operation of said means and machine.

5. In a machine of the class described and in combination, a container body forming machine, means for attaching pintles to blanks, and means for automatically conveying pintled blanks into position to be operated upon by said body forming machine.

6. In a machine of the class described and in combination, a container body forming machine, and an attachment for said ma-

chine including means adapted to be connected to said body forming machine for mounting pintles on blanks, means for conveying the pintled blanks into position to be operated upon by the body forming machine, and drive mechanism for said pintle mounting and conveying apparatus, connected to the drive of the body forming machine, the construction being such that said machine and attachment operate in synchronism.

7. In a machine of the class described and in combination, a container body forming machine having a guideway adapted to receive blanks for initial engagement by a device traveling along said guideway, means for mounting pintles on blanks, and conveying means extending transversely to said guideway for transferring pintled blanks from the pintle mounting means automatically onto said guideway in position for engagement by said device.

8. In a machine of the class described and in combination, a container body forming machine, means for mounting pintles on blanks, means for successively delivering the blanks to said machine in position to be initially engaged thereby, and means for registering the blanks in said position.

9. In a machine of the class described and in combination, a container body forming machine, means for mounting pintles on blanks, means for successively delivering the blanks to said machine in position to be initially engaged thereby, and means for registering the blanks in said position, said last named means including an element shiftable in synchronism with the operations of said pintle-mounting means, and with said machine.

10. In a machine of the class described and in combination, a container body forming machine having a guideway adapted to receive initially pintled blanks, conveying means extending transversely to said guideway and adapted to shift the blanks successively step by step toward and onto said guideway, and means adjacent said conveying means for mounting pintles upon the blanks shifted thereby.

Signed at Winston-Salem in the county of Forsyth and State of North Carolina, this 17th day of June A. D. 1921.

CHARLES V. STRICKLAND.
